UNITED STATES PATENT OFFICE

CHARLES M. STONER, OF CHAMBERSBURG, PENNSYLVANIA, ASSIGNOR TO THE WOLF COMPANY, OF CHAMBERSBURG, PENNSYLVANIA, A CORPORATION OF PENNSYLVANIA

CUTTING MACHINE

Application filed July 21, 1928. Serial No. 294,431.

This invention relates to machines of the type that are used for cutting relatively coarse materials to predetermined smaller sizes. Some of the materials which can be used in the machine are corn and other grains, paper, pulp, cork, dried milk, rags, roots, herbs, spices, bark, bones, tobacco stems, leaves, shavings, leather, etc.

An object of the invention is to provide a cutting machine wherein the material is delivered to the cutters in a direction coinciding to the direction of rotation of the cutters.

Another object is to provide a screen for cutting machines wherein there are three separate zones for grading the material.

Another object is to provide a perforated guide wall eccentric to the cylindrical cutter rotor, to guide the material from the hopper to the cutters.

Another object is to produce an efficient, strong and durable cutting machine which may be economically constructed and operated.

Other objects and advantages will hereinafter appear.

The views of the drawings are:

Fig. 1 is a vertical longitudinal section of a cutting machine constructed according to my invention, as seen on the line 1—1 of Fig. 2;

Fig. 2 is a vertical transverse section as seen on the line 2—2 of Fig. 1; and

Fig. 3 is an end view.

Referring to the drawings, the machine includes a base 1 having an open bottom. The base 1 carries a casing 2 that is connected to the base by a hinge 3. On the side of the base opposite to the hinge there is a clamping device 4 for retaining the casing in position on the base. When the clamping device is released and the casing 2 swung back on the hinge 3, the chain 5 will support the casing, as will be readily understood.

The ends of the base 1 carry ball bearings 6 in which is mounted a shaft 7 that extends longitudinally of the machine and projects through the ends of the base. On end of the shaft 7 there is a pulley 8.

The shaft 7 has fixed thereon a plurality

of circular disks 9, to the peripheries of which are mounted cylinders 10. In the present instance there are five disks and four cylinders used, and these parts provide a reel for supporting a plurality of arcuate cutting knives 11. The knives 11 may be detachably mounted in the manner shown, and be retained in position by means of keys 12.

The top of the casing 2 carries hopper 13, the top of which is closed by a slide 14.

Beneath the slide 14 there is a spreader 15 on which the material falls as it is fed into the machine. The spreader 15 divides the material into two streams.

At the bottom of the hopper 13 there are two inclined baffle plates 16 and 17 on to which the streams of material fall.

The lower edges of the plates 16 and 17 are so disposed as to provide an elongated slot 18 through which the material will flow in the form of a sheet that will be substantially coextensive with the cutting reel, as will be readily understood.

The interior of the machine is provided with a screen including three zones, constructed as follows: The base 1 has mounted therein a semi-cylindrical screen 19 which is disposed in close proximity to the outer surfaces of the cutting blades 11. This screen is reinforced by a plurality of rectangular bars 20.

The front of the casing 2 between the baffle plate 17 and the clamping device 4 is provided with an arcuately formed screen 21. This screen is spaced further from the exterior of the cutting reel, and the surface of the screen contiguous to the blades 11 carries a plurality of cutter bars 22. The bars 22 may be detachably connected to the screen by means of bolts 23.

On the side of the casing 2 opposite to the screen 21, there is another screen 24, which is of involute form. At the lower edge of the screen 24 there is a cutter bar 25, similar in form to the cutter bars 22.

The material comes in contact with the knives 11 in a gentle manner through the novel disposition of the screen 24. It will be noted that the upper portion of the screen 24 is disposed at a considerable distance from

the surface of the cutting reel, while the lower edge of the screen 24 lies adjacent to the upper edge of the screen 19. Thus, a funnel-shaped passage is provided through 5 which the material descends in a direction substantially tangential to the surface of the revolving cutting reel.

Therefore, when the material approaches the cutter bar 25 a percentage thereof will be sheared by the knives 11, and the material which has thus been divided will pass through the openings in the screen 19. The remaining material will be carried upwardly by the centrifugal force of the cutting reel and then be directed against the cutter bars 10 22 and screen 21. This action should shear the material sufficiently to permit it to pass through the screens but if the material is not divided at this point it will be carried 15 forward towards the screen 24 where the operation will be repeated.

Attention is directed to the limited space separating the knives 11 and the cutter bars. This space is reduced to the minimum so as to prevent the material from accumulating 25 between the revolving reel and the stationary parts of the machine, as the friction thereby produced by the excess material would consume excessive power. In this way the input is regulated to the capacity of the machine. 30 The material cannot collect and remain inactive, but is acted upon in the limited space which is provided by my construction. It will also be apparent that the centrifugal 35 action of the material causes it to roll over the inside surfaces of the screens, the fine material being forced through the perforations of the screens while the uncut material will remain until it is reduced to the required size before it can pass through the 40 perforations.

The invention set forth herein is, of course, susceptible of various modifications and adaptations.

45 I claim:

1. A cutting machine, comprising a rotor with cutters thereon, a casing housing said rotor, a fixed blade within said casing adjacent the cutters, a hopper above the rotor, 50 deflectors for material from the hopper, between the hopper and the rotor, and a wall within the casing, eccentric to the rotor, to feed the material from the deflectors into the path of the cutters.

46 2. A cutting machine, comprising a rotor of closed surface with cutters thereon, a casing housing said rotor, a fixed blade within said casing adjacent the cutters, a hopper above the rotor, deflectors between the hopper 55 and the rotor, and a curved wall within the casing, eccentric to the rotor, to guide the material from the deflectors into the path of the cutters.

47 3. In a cutting machine, a rotor provided 60 with cutters thereon, a casing housing said

70 rotor, a screen arranged about said rotor, having an opening therein, and having a portion of substantially involute form adjacent said opening, a hopper arranged above said opening, and a baffle plate between said hopper and that end of the screen opposite the involute portion thereof, arranged in such manner that material from the hopper is incident on the baffle plate, and is then deflected tangentially into the tapered opening between the rotor and the said involute portion.

4. In a cutting machine, a rotor provided 75 with cutters thereon, a casing housing said rotor, a screen arranged about said rotor, having an opening therein, and having a portion of substantially involute form adjacent 80 said opening, a hopper arranged above said opening, a baffle plate between said hopper and that end of the involute portion defining one edge of the opening in the screen, and another baffle plate extending in a direction opposite to that of the first-mentioned baffle plate, and connecting said hopper and the other end of the screen, whereby at least 85 a portion of the material from the hopper is deflected from the first-mentioned baffle plate to the second-mentioned baffle plate, and thence tangentially into the opening between the 90 rotor and the said involute portion.

5. In a cutting machine, a rotor, at least 95 one cutting element on said rotor, a screen partly enclosing said rotor and having an opening therein, at least one cutting element 100 fixed on the exterior of said screen and adapted to cooperate with said first-mentioned cutting element, a portion of said screen defining one edge of the opening being of involute form, a hopper above said opening, and a baffle connecting said hopper and that edge of the opening opposite the portion 105 of involute form, whereby the material from the hopper is deflected from the baffle plate into the opening between the rotor and the said involute portion so that substantially 110 the first blow of the rotor on the material to be crushed is a shearing action between the cooperating cutting elements.

6. In a cutting machine, a rotor, at least 115 one cutting element on said rotor, a screen partly enclosing said rotor and having an opening therein, at least one cutting element 120 fixed on the exterior of said screen and adapted to cooperate with said first-mentioned cutting element, a portion of said screen defining one edge of the opening being of involute form, a hopper above said opening, a baffle plate connecting said hopper and that end of the involute portion defining the 125 edge of the opening, and a second baffle plate extending in a direction opposite to that of the first-mentioned baffle plate, and connecting said hopper to the other edge of said opening, whereby at least a portion of the material from said hopper is deflected from the 130

first-mentioned baffle plate onto the second-mentioned baffle plate, and from thence into the opening between the rotor and the said involute portion, so that substantially the first blow of the rotor on the material to be crushed is a shearing action between the cooperating cutting elements.
